(57) **CLAIM**

The ornamental design for a power unit cover for an industrial vehicle, as shown and described.

DESCRIPTION

FIG. 1 is a back, top, left perspective view of a power unit cover for an industrial vehicle, showing our new design; FIG. 2 is a back, top, right perspective view thereof; FIG. 3 is a back, bottom, right perspective view thereof; FIG. 4 is a back, bottom, left perspective view thereof; FIG. 5 is a back elevational view thereof; FIG. 6 is a front elevational view thereof; FIG. 7 is a right side elevational view thereof; FIG. 8 is a left side elevational view thereof; FIG. 9 is a top plan view thereof; and, FIG. 10 is a bottom plan view thereof.

The broken lines shown in the figures are for the purpose of illustrating the environmental structure and form no part of the claimed design.
